US00D835220S

(12) **United States Design Patent** (10) Patent No.: **US D835,220 S**
Treadway et al. (45) Date of Patent: ** Dec. 4, 2018

(54) **BATTERY POWERED SKATEBOARD**

(71) Applicant: **Acton, Inc.**, Mountain View, CA (US)

(72) Inventors: **Peter Treadway**, Sunnyvale, CA (US);
Janelle Wang Treadway, Sunnyvale, CA (US)

(73) Assignee: **Acton, Inc.**, Mountain View, CA (US)

(**) Term: **15 Years**

(21) Appl. No.: **29/581,208**

(22) Filed: **Oct. 17, 2016**

(51) LOC (11) Cl. **21-02**

(52) U.S. Cl. **D21/765**

(57) **CLAIM**

The ornamental design for a battery powered skateboard, as shown and described.

DESCRIPTION

FIG. 1 is a top, front, and right-side perspective view showing the battery powered skateboard; FIG. 2 is a bottom, rear, and left-side perspective view thereof:

FIG. 3 is a right-side view thereof;

FIG. 4 is a left-side view thereof;

FIG. 5 is a front view thereof.

FIG. 6 is a rear view thereof;

FIG. 7 is top view thereof; and,

FIG. 8 is a bottom view thereof. The broken lines in FIGS. 1 through 8 illustrate portions of the battery powered skateboard that are not part of the claimed design.
